DESIGN FOR A COMBINED LAMP BRACKET AND TIMER FOR COOKSTOVES

Montgomery Ferar, Detroit, Mich., assignor to
Florence Stove Company, Gardner, Mass., a
corporation of Massachusetts

Application April 11, 1947, Serial No. 138,320

Term of patent 7 years

(Cl. D31—25)

To all whom it may concern:

Be it known that I, Montgomery Ferar, a citizen of the United States, residing at Detroit, in the county of Wayne and State of Michigan, have invented a new, original, and ornamental Design for a Combined Lamp Bracket and Timer for Cookstoves, of which the following is a specification, reference being had to the accompanying drawing, forming a part thereof.

Figure 1 is a perspective view of a combined lamp bracket and timer for cookstoves, showing my new design.

Fig. 2 is an end elevational view of the same.

I claim:

The ornamental design for a combined lamp bracket and timer for cookstoves, substantially as shown.

MONTGOMERY FERAR.
